(57) **CLAIM**

We claim the ornamental design for a conveyor pulley including a wear indicator, as shown and described.

DESCRIPTION

FIG. 1 is a perspective view of an embodiment of a conveyor pulley including a wear indicator showing the new design; FIG. 2 is a left side view thereof, the right side being a mirror image thereof;

FIG. 3 is an enlarged left side view thereof;

FIG. 4 is a top view thereof, the bottom, front, and back views being a mirror image thereof;

FIG. 5 is a perspective view of a second embodiment of a conveyor pulley including a wear indicator showing the new design;

FIG. 6 is a left side view thereof, the right side being a mirror image thereof; and,

FIG. 7 is a top view thereof, the bottom, front, and back views being a mirror image thereof.

The dash-dot lines in FIGS. 1-7 indicate unclaimed portions of the conveyor pulley, and form no part of the claimed design. The conveyor pulley including a wear indicator is shown with symbolic breaks in its length. The appearance of any portion of the article between the break lines form no part of the claimed design.
